POST HOLE DIGGER BOOM

Rawlen T. Smith, 4170 Dover St.,
Wheatridge, Colo. 80033

Filed Nov. 29, 1967, Ser. No. 9,574

Term of patent 14 years

Int. Cl. D15—04

U.S. Cl. D39—1

FIG. 1

FIG. 2

FIG. 3

FIG. 4

FIG. 5

FIG. 1 is a side elevation of the post hole digger boom of the invention embodying my new design;

FIG. 2 is a front elevational view;

FIG. 3 is a top plan view;

FIG. 4 is a front quarter perspective; and

FIG. 5 is a rear quarter perspective thereof.

The broken line showing is for illustrative purposes only.

I claim:

The ornamental design for a post hole digger boom, as shown and described.
